DESIGN FOR A JODHPUR

William E. Justin, Fort Worth, Tex.

Application May 27, 1941, Serial No. 101,181

Term of patent 7 years

To all whom it may concern:

Be it known that I, William E. Justin, a citizen of the United States and resident of Fort Worth, in the county of Tarrant and State of Texas, have invented a new, original, and ornamental Design for a Jodhpur, of which the following is a specification, reference being had to the accompanying drawing, forming a part thereof.

Fig. 1 is a perspective view of one side of a jodhpur, showing my new design.

Fig. 2 is a perspective view showing the other side of the same.

The dominant feature of the design resides in the combination of a rear quarter having its front edges concave and extending from the front of the heel upwards and forwards, with a vamp portion having its rear edges concave and opposed to said front edges and dividing off in conjunction with said front edges gusset areas at both sides of the jodhpur.

I claim:

The ornamental design for a jodhpur, as shown and described.

WILLIAM E. JUSTIN.
